UNITED STATES PATENT OFFICE.

PETER HAMMER, OF BROOKLYN, NEW YORK.

WIRES MATTRESS.

Application filed December 31, 1921. Serial No. 526,238.

To all whom it may concern:

Be it known that I, PETER HAMMER, a citizen of Austria, residing at Brooklyn, in the county of Kings and State of New York, have invented new and useful improvements in Wire Mattresses, of which the following is a specification.

My invention consists of a new and improved form of wire mattress and method of making same. An object of the invention is to make a mattress fabric of a single continuous strand of wire. By making the fabric of one single continuous wire, the strain caused by the weight of a body lying on the mattress is distributed over the entire fabric. Heretofore mattresses have been made of a number of separate strands of wire and the result is that the wires on which the weight is placed sag down and become loose.

Another object of the invention is to place crimps in the wire which by the manner of construction hereinafter described, are brought opposite each other to enable the clips to be placed at regular intervals in a straight line across the fabric.

Another advantage of the invention lies in the fact that by crossing the wire as it is passed through the helical springs an even tight strain can be given the wire so that in the entire fabric the tension of the wire is evenly distributed on all the helicals.

Another advantage of my construction is that by having the wire continuous, it simply goes through the end loop of each helical and does not extend into the helical itself. In mattresses which are made with a series of single strands, each strand is twisted so that the ends are inside each helical, causing dirt to accumulate therein, and giving an additional hiding place for vermin.

In the accompanying drawings, Figure 1 is a plan view of a mattress constructed according to my invention.

Figure 2 is an enlarged detail view of a portion of one of the end members, with a helical spring attached thereto and a portion of the wire fabric going through the eye of the helical.

The device consists of a frame made in a well-known manner having ends 3 and side members 4. The side members are attached

to the end members by a pair of helicals 5. The fabric consists of a continuous wire 6 having pre-determined crimps 7. The crimps are formed in reverse direction from each other.

The fabric is formed by fastening one end of the continuous wire to a loop 8 in the first of a series of helical springs 9. These helical springs 9 are placed on both end members in staggered relation to each other. The wire is then carried to the opposite helical on the other end of the frame, passed through the loop and then crossed and carried back to the helical adjoining the one from which it started. The wire is then passed through the adjoining helical on the side of the helical which is farthest away from the point where the wire started. The wire is then crossed and carried to the opposite helical and crossed again after passing through the helical, and so on back and forth until the entire frame is covered and it is finally secured to the last helical at that end of the frame from which it started. The crossing of the wire as it passes through each helical forms a loop at each helical, giving room for a certain amount of play or give of the wire in the helical.

It is therefore apparent that a continuous wire fabric is thus formed having in effect a separate series of longitudinal extending wire members, but in reality being made of one single strand. Clips 10 are placed in the crimps 7, thus holding the longitudinal strands firmly together so that the whole fabric formed of continuous wire is strongly and firmly held together.

I claim:

A wire mattress comprising end members of a suitable frame and springs secured to said end members, a fabric consisting of a single continuous wire bent back and forth to form a plurality of integrally connected strands in spaced and substantially parallel arrangement, contiguous strands being crossed only near the connected ends thereof to form bights or loops each in engagement with one of said springs, whereby the stresses on adjacent strands are transmitted through the integrally connected ends thereof and the fabric as a whole retains its ri-

gidity due to substantial counter-balancing of these stresses, crimps regularly spaced throughout the length of said wire so located and disposed as to provide oppositely positioned seats for connected links in staggered arrangement, and spacing and sustaining links in said crimps.

In testimony whereof I have hereunto set my hand in the presence of two subscribing witnesses.

PETER HAMMER.

Witnesses:
